[57] ABSTRACT

Improved inverted pump/grinder construction is presented herein. At least one sharp-edged protrusion is located below the impeller/shredder zone to interrupt the spinning motion of objects, which tend to become entangled on the impeller. This interruption by the protrusion renders such objects more readily subjected to the impeller/shredder action and thereby prevents formation of a large tangled mass.

SNAGGING DEVICE FOR INVERTED GRINDER

The invention herein described was made in the course of or under a contract with the United States Department of Interior.

BACKGROUND OF THE INVENTION

U.S. Pat. No. 3,366,339, Fair is directed to a system for the separate transport of sanitary sewage and storm water, utilizing a pressurized system for transport of the sanitary sewage. The term "sanitary sewage" is used to designate water discharged from sanitary fixtures and collected as wastewater after serving its primary purpose, as well as water serving the purpose of carrying away other waste matter from households, mercantile, commercial and industrial establishments.

According to the concept in the Fair patent, sanitary sewage would be intercepted in individual buildings, from which it would be pumped into pressurized street sewers. Because rather small sized tubing and piping would be required for transmitting sewage, a reduction in particle size of much of the solid matter encountered in sanitary sewage is necessary prior to pumping such material from individual buildings into the street sewage lines. The most practical method proposed for the reduction in particle size is by means of grinding, shredding or combined grinding and shredding.

The most practical construction is effected by mounting the grinder in an upside-down position in a holding tank and providing a relatively large access opening into the grinding region so that the velocity of sanitary sewage entering the grinder will be sufficiently low that particles of glass or metal will settle to the bottom of the holding tank and not damage the grinder or settle in (and impede flow in) the high pressure effluent line. A pump is provided between the grinding zone and the piping and in flow communication with both in order to transmit the sanitary sewage from the building. Thus, the several components acting in combination provide the functions of grinding, storage and pumping.

Attempts to use a standard commercial grinding mechanism for the grinding function created such a tremendous viscous drag in the inlet hopper that current input to the grinder motor was nearly ten times the normal level. In order to satisfactorily overcome such high levels of viscous drag an increase in the horsepower of the grinder motor would have been necessary to the extent that normal household circuits would not be adequate to supply the required power (e.g., 1 1/2 hp or greater).

SUMMARY OF THE INVENTION

A solution to the problem has been made possible partly by a reduction in speed of the motor driving the grinder but more significantly by the streamlining of the flywheel assembly and provision of at least one sharp-edged protrusion located close to and below the impeller/shredder zone to interrupt the spinning motion of any materials being dragged by the impeller to render such materials more readily subject to the impeller/shredder action and thereby prevent the formation of large tangled masses.

BRIEF DESCRIPTION OF THE DRAWING

The exact nature of this invention as well as the objects and advantages thereof will be readily apparent

from consideration of the following specification relating to the annexed drawing, wherein:

FIG. 1 is a vertical view partly in section showing the interrelated construction of the grinding mechanism, drive motor and pumping mechanism and, in combination therewith, a ring-shaped device constituting an embodiment of the instant invention and

FIG. 2 is a plan view of the ring configuration shown embodied in the structure of FIG. 1.

DESCRIPTION OF THE PREFERRED EMBODIMENT

In FIG. 1 the combined pump/grinder mechanism is shown affixed to mounting flange 11 to facilitate disposition of the grinder mechanism within a storage tank (not shown). Motor 12 simultaneously drives flywheel 13 (via shaft 14) and pump 16 (via belt drive 17).

Cylindrical housing 18 encloses both shaft 14 and delivery tube 19 leading from suction zone 21 (above flywheel 13) to the inlet of pump 16. Level control means (not shown) are employed to energize a thermal time delay relay (not shown) which in turn operates switching means for motor 12. The thermal relay is employed to provide a predictable delay in both "on" and "off" switching functions. Such systems are widely employed as level controllers in modern day automatic clothes washers and dishwashers. Bearing/seal assembly 22 prevents liquid from entering housing 18 along shaft 14.

Flywheel 13 affixed to the lower end of shaft 14 is made with a streamlined configuration to minimize viscous drag thereon as it is rotated in the surrounding liquid and impellers 23 are rigidly affixed thereto or formed thereon. Grinding and shredding functions are provided through the interaction of impellers 23 and shredder ring 24 having lugs 26 of various shapes and projecting a short distance from the shredder ring 24.

It was determined by test that selection of the motor speed had a very significant effect on the viscous drag encountered in operation of the unit. Thus, by reducing motor speed from 3,450 rpm to 1,725 rpm the viscous drag was reduced by at least 85 percent and by providing a streamlined flywheel, the viscous drag was further reduced by at least a third.

In testing it was found, however, that when certain classes of foreign objects were introduced into the inverted grinder as heretofore described and operated, these objects almost inevitably became entangled under the lip of an impeller and were simply pulled through the water by the impeller and evaded the shredder/impeller action. Thus, objects such as strings, bits of cloth, rubber and the like in becoming so entangled with the impeller gradually became more tightly twisted, knotted and entangled with each other until they formed unmanageable masses. The dragging of such an unmanageable mass through the water greatly increased the viscous drag and would have increased the required motor horsepower. In fact, the horsepower demands for such a system would have increased to the point at which normal (115 volt) household circuits would not be adequate to supply the necessary power (e.g., 1 1/2 hp or higher).

It was found that by introducing at least one sharp-edged protrusion, or snagging means, immediately

below the impeller/shredder zone extending inwardly, the spinning motion of materials entangled with the impeller is stopped long enough by such a protrusion to permit the normal upwardly directed low velocity water flow to carry such materials into the cutting/shredding region before there is a chance to develop a large tangled mass.

Although the requisite protrusion, or snagging means, to interrupt the constant rotation of entangled material may be cast or otherwise made an integral part of shredder ring 24 at some position below lugs 26, a convenient way for the introduction of such a protrusion is by means of a separate piece in the form of a ring having the desired number of protrusions in the desired configurations. Ring 27 inserted in the vertical clearance between shredder ring 24 and suction bell 28 presents four protrusions 29, 31, 32 and 33. In any construction employing a single or multiple protrusions one protrusion e.g. protrusion 29 constitutes the snagging means and should be large enough to project radially inwardly toward the shaft axis further than lugs 26 and any other protrusions thereby functioning to snag string, fabric, rubber, etc., that might become entangled on one or more impellers.

If desired, each of the other protrusions employed 25 may be made in identical shape or (as in the case of protrusion 31) may be in the form of a hook-shaped tooth. Whether or not any tooth configuration is employed all protrusions must have sharp leading edges in order to provide a slashing action. The disposition of 30 the leading edges of the protrusions relative to the direction of rotation of the impeller must be as is shown in FIG. 2.

The protrusions themselves should be made of some hardened material such as 410 stainless steel hardened 35 to 35-55 Rockwell C, tungsten carbide or similar material able to provide a durable sharp leading edge. If the protrusions are provided as inserts in ring 27, ring 27 itself may be made of any strong, corrosion-resistant material, since it would only position the protrusions 40 relative to the impeller/shredder zone.

By providing and properly locating the sharp-edged snagging means of this invention the development of tightly twisted knotted masses dragged by one or both impellers is prevented and the utilization of a smaller 5 horsepower motor is made possible.

Mounting flange 11, flywheel 13, shaft 14, delivery tube 19, bearing/seal assembly 22, impellers 23, shredder ring 24 and suction bell 28 are made of conventional materials for the requisite performance 10 required thereof.

What I claim as new and desire to secure by Letters Patent of the United States is:

1. In an apparatus for the grinding/shredding of solid materials contained in a liquid flow and the pumping of 15 the resulting mixture under pressure wherein the grinding/shredding action is accomplished by the interaction of flywheel-mounted impellers and a stationary shredder ring, the flywheel being mounted on a vertically-disposed shaft and the shaft depending from the drive means therefor, the liquid flow entering the impeller/shredder zone from below and being pumped away from above the impeller/shredder zone, the improvement comprising:

a. a single stationary snagging means mounted below the impeller/shredder zone for snagging material entangled on and dragged by one or more impellers, said snagging means comprising annular means underlying said shredder ring and having an inwardly extending tooth-like projection presenting a sharp leading edge transverse to the direction of liquid flow, said projection being disposed closer to the shaft axis than any portion of said shredder ring.

2. The improvement recited in claim 1 wherein said annular means includes a plurality of additional inwardly extending tooth-like projections, each of which has a sharp leading ledge that is transverse to the direction of liquid flow, said additional projections extending a lesser distance inwardly toward said shaft axis than said first named tooth-like projection.
